UNITED STATES PATENT OFFICE.

PHILIP ROSENBERG, OF BROOKLYN, NEW YORK.

HAT LINING AND SIZE REDUCER.

Application filed February 13, 1928 Serial No. 253,829.

My invention relates to improvements in linings for hats; especially hats which are to afford a good fit upon the wearer's head.

An object of the invention is to provide a lining for a hat of such a character that the size of the hat can be adjusted as desired, in a simple, quick, and easy manner, without requiring either cutting or stitching or any alteration whatever in its structure or appearance.

The nature and advantages of the invention are fully set forth in the following description; and the novel features are pointed out in the appended claims. But this disclosure is explanatory only, and I may vary the details of construction and design without departing from the spirit of the invention, or exceeding the scope thereof.

On the drawings—

20 Figure 1 is a cross section of a lining for a hat according to my invention,

Figure 2 is a horizontal section on the line 2—2 of Figure 1, looking in the direction of the arrows,

25 Figure 3 is a side view of an adjusting strip to be inserted into the lining, and

Figure 4 is a section on line 4—4 of Figure 3.

On the drawings, the same numerals identify the same parts throughout.

In the particular description of the invention as illustrated, I use the numeral 1 to indicate the body of the lining, which is closed at the top by a piece of material 2 and open at

35 the bottom. The lining can thus be inserted into a hat and secured in place. It can be made out of any suitable material secured together at its opposite ends with the top 2 stitched in place along the upper edge of the

40 body 1. Encircling the lining adjacent the opposite edge which surrounds the open bottom of the lining is a portion of strip 3 fastened to the body of the lining 1 by an upper row of stitches 4 and a lower row of stitches

45 5. This strip forms with the lining adjacent the open lower end or bottom, an annular pocket 6 surrounding the lining, and when the lining is put into a hat, usually a woman's hat, the strip 3 will be between the lining and

50 the crown of the hat, and will be entirely hidden from view. The sleeve is intended to receive and contain a strip or pad of some kind of filling material that can be made as thick as desired to adjust the size of the

55 hat to which the lining is attached, that is to say, the inside dimensions of the crown as

required. If the hat would otherwise be too large, the insertion of a pad, such as shown at 7 of the right thickness into the pocket 6, will, of course, reduce the size of the hat by 60 the necessary amount to make it fit the wearer's head in the proper manner.

The ends of the body 1 which may consist of a strip of cloth rolled into the form of a tube or sleeve to bring the ends together, 65 may be diagonal, as indicated at 8, and the two edges may be sewed or stitched from the top 2 down as far as the line of stitches 4. From that point on, these two edges may be un-sewed as far as the lower row of stitches 5 to provide a slit 9 which gives admission to the pocket 6 from the inside of the lining 1. The diagonal edges of the ends of the body 1 may be stitched together below the stitches 5 at the edge or rim of the lining 1. The ends 70 of the strip 7 are preferably abrupt or square, so that to insert the strip into the pocket 6, one needs only to open the entrance 9 to the pocket 6 so as to insert the corner of one end of this strip, and then the whole strip can 75 easily be pushed into the pocket 6.

These strips can be kept in stock and can be of varying thicknesses. They are generally made of two layers of cloth 10 with a layer 80 of stiffening material, such as coarse gauze 11 between them and secured together by stitches 12. Such a strip can, of course, be taken out or replaced whenever the wearer wishes.

The extent to which the ends of the body 1 overlap at the slit 9 is indicated by the numeral 13. If desired, the ends of the strip 3 may also be cut on the diagonal and be un-stitched to provide an opening 14 similar to the opening 9. The overlapping ends of the strip 3 are indicated by the numeral 15 in Figure 1.

With a hat lining according to my invention, the size of the hat in which the lining is placed can be adjusted without alteration of the hat or the lining, merely by putting a strip 7 of the required thickness into the pocket 6. The strip 7 is entirely hidden, and the adjustment of the size of the hat is thus accomplished without changing in any manner the appearance of the hat or of the lining 105 1 within it.

The pad or strip 7 can be made of any suitable material and in layers, as shown, or in other ways. It can be removed and shortened by cutting off at either end, if desired, to give the right fit. I can also sew up the diagonal ends of the strip 3, to close the opening 14, as 110

the opening or slit 9 in the lining 1 is sufficient.

In practice the body 1 may be made in one piece or several pieces and the strip 3 may be attached either to the outside or to the inside of same.

What is claimed is:—

1. A lining for a hat comprising a body shaped to fit the interior of the hat, said body having a portion attached adjacent its lower edge to the body and extending circumferentially thereof, the upper edge of said portion also being secured to the body, the lining and said portion thus providing a continuous annular pocket closed at top and bottom, said pocket having an opening and a flexible strip of filling material in the pocket and remov-

able through said opening to adjust the size of the hat to the head of the wearer.

2. A lining for a hat comprising a body 20 consisting of a piece of cloth with diagonal edges secured together, a strip secured to the outside of the lining to provide a pocket there-between, part of the diagonal edges of the lining between the top and bottom edges of 25 the strip being un-stitched to provide an entrance opening with diagonal edges to said pocket and permit the insertion of filling material to adjust the size of the hat according to the wearer's head. 30

In testimony that I claim the foregoing as my invention, I have signed my name hereto.

PHILIP ROSENBERG.
